UNITED STATES PATENT OFFICE

135,152

DESIGN FOR A COMBINED CAKE AND CANDLE HOLDER

Clarrajay Frenger, Las Cruces, N. Mex.

Application July 29, 1942, Serial No. 107,734

Term of patent 3½ years

To all whom it may concern:

Be it known that I, Clarrajay Frenger, a citizen of the United States, residing at Las Cruces, in the county of Dona Ana and State of New Mexico, have invented a new, original, and ornamental Design for a Combined Cake and Candle Holder, of which the following is a specification, reference being had to the accompanying drawings, forming part thereof.

It is understood that the ornamentation on the flat top of the holder as shown in Figures 1 and 3 is continuous throughout the entire circumference of said part.

I claim:

The ornamental design for a combined cake and candle holder, as shown and described.

CLARRAJAY FRENGER.
